UNITED STATES PATENT OFFICE.

ERNEST H. DUVAL, OF MONROE, MICHIGAN, ASSIGNOR TO GEORGE W. SWIFT, JR.,
INCORPORATED, OF BORDENTOWN, NEW JERSEY, A CORPORATION OF NEW
JERSEY.

STAMPING-MACHINE.

1,393,513.

Specification of Letters Patent. Patented Oct. 11, 1921.

Application filed March 13, 1920. Serial No. 365,564.

To all whom it may concern:

Be it known that I, ERNEST H. DUVAL, a citizen of the United States, residing at Monroe, in the county of Monroe and State 5 of Michigan, have invented new and useful Improvements in Stamping-Machines, of which the following is a specification.

This invention has reference to paper box-making machines, and particularly to a 10 printing or marking attachment therefor.

An object of the invention is to provide a paper box making machine with normally inactive means which does not interfere with the construction or operation of the machine, and whereby a part of the box when 15 brought to engage therewith will have impressed thereon direction, designating, description matters or characters.

A further object is to mount on a box 20 making machine, a printing roller having means whereby the same is held inactive or in non-printing position and also having means for preventing the same from making more than one impression on a paper board, 25 when the latter is brought to engagement therewith, regardless of the length thereof or the time required in its travel under the printing roller.

A still further object of the invention is to 30 arrange on one of the shafts of the crimping or scoring device of a paper box machine a feed roller, on an adjacent shaft an impression roller carrying type, to provide means whereby the inking roll will be 35 brought over the type, and to also provide means whereby the printing roll is normally held immovable regardless of the turning of the shafts, motion being imparted to the said printing roll by the engagement of the 40 paper board between the same and the feed board, and means being further provided for holding the printing roll after the same has made an impression upon the paper board until the latter has been moved from 45 between the impression and printing rolls, so that only one impression can be made on the board.

It is a still further object of the invention 50 to produce a printing or marking attachment for paper box machines in which a printing roll of a novel construction is provided, the same having means whereby type or other characters may be removably secured thereon, means for inking such type 55 or characters, and means for holding the

roll immovable until after the same has been brought to printing or marking position, so that only one impression on a single article will be made.

Many other objects and advantages will 60 present themselves as the nature of the invention is better understood, reference being had to the accompanying drawings in which there is illustrated a simple and satisfactory modification of the improvement reduced to 65 practice, the nature of the invention being such, however, as to render the same susceptible to modifications and such modifications falling within the scope of what is claimed. 70

In the drawings:—

Figure 1 is a top plan view of the improvement.

Fig. 2 is a sectional view approximately 75 on the line 2—2 of Fig. 1.

Fig. 3 is a sectional view approximately on the line 3—3 of Fig. 1.

Fig. 4 is a sectional view similar to Fig. 2 but showing how the printing roller is halted after an impression has been made thereby 80 on a paper board.

Figs. 5 to 7 illustrate details showing the construction of the printing or impression roller.

Fig. 8 is a longitudinal sectional view 85 through the inking roller.

Fig. 9 is a sectional view approximately on the line 9—9 of Fig. 1.

Fig. 10 is a detail sectional view approximately on the line 10—10 of Fig. 9. 90

Referring now to the drawings in detail the numeral 10 designates an I-beam which is a part of the frame of the box making machine. Below the I-beam 10 are superimposed longitudinally arranged shafts 11 95 and 12 that carry the co-engaging score rolls 13—13 and 14—14 respectively. The shafts are revolved by the usual means (not shown) and the paper or board is creased or scored by the rolls 13 and 14. 100

To the lower flange of the I beam 10 is secured the support of my improvement. The support includes two spaced bars 15 that have their outer ends flanged to form the same with jaws 16 that engage one of the edges of the lower flange of the beam 10. Each of the plates 15 has its upper surface provided with teeth 17 and these teeth are engaged by similar teeth 18 on the movable jaw members 19 of the supports. The 110

blocks comprising the body portions of the movable jaws 19 have elongated slots 20 therethrough, and the plates 15 have upstanding bolts 21 that pass through the slots. These bolts are engaged by nuts 22 that contact with the outer faces of the block or body members of the movable jaws 19. The jaws 19 engage with the inner edge of the lower flange of the I beam opposite 10 that engaged by the outer fixed jaw 16.

The plates 15, upon their outer ends have lining openings that receive therethrough a shaft 23. The numeral 24 designates binding elements carried by the plates 15 and 15 which contact with the shaft 23 to hold the same immovable.

On the shaft 23 is a bracket 25. The bracket 25 has a rounded slotted portion 26, the same having an opening therethrough 20 receiving the shaft 23. The numeral 27 designates a binding element that is designed to compress the slotted portion of the bracket to cause a tight frictional engagement between the same and the shaft 23, and consequently permit of the angular adjustment of the bracket with respect to the shaft, but effectively holding the said bracket at such adjustment.

The bracket has on its rear end two spaced 30 upstanding lugs 28. Passing through openings in these lugs and the body of the bracket are shafts 29. On the upper end of each of the shafts 29 there is secured one end of a coil spring 30. The coil portions of the flat 35 springs 30 are wound around the respective shafts 29, as clearly illustrated by the drawings, and the spring 30 is concealed by a cap or casing 31 that is arranged thereover and is secured to the lugs in any desired or preferred manner. The shafts 29 pass through bearing openings in the said cap or casing 31, and are preferably provided with enlargements or other means for holding the same against downward longitudinal movement.

On the lower end of each of the shafts 29 there is keyed or otherwise secured a sheave wheel 32.

The bracket 25 has its end opposite that 50 provided with the lugs 28 depressed to form the same with a reduced lip 33. This lip is lapped by a similar lip 34 formed on one end of a plate which provides a bracket extension 35. The lip 34 has an elongated slot 55 or opening 37 therethrough, and the lip 33 carries a bolt 38 that passes through the slot. The bolt is engaged by a nut 39 which also preferably contacts with a washer 40 to effect a binding engagement between the 60 lips 33 and 34, and consequently a locked adjustment between the bracket 28 and its extension 35. The extension 35 has its outer end widened and its sides preferably formed with lugs or extensions 40'. Secured to the 65 widened sides of the extension 35, at the

said lugged corners thereof, preferably by removable means 41, are bearing brackets 42. The brackets 42 have journaled therein a shaft 43. The shaft preferably has its central portion enlarged and threaded at 70 the ends thereof. These threads are engaged by internal threads on cap plates or disks 44. The cap plates or disks clamp on the shaft 43 a wooden roll 45 that has on its periphery a felt facing 46. This provides 75 the inking roll, a quantity of ink being fed to the felt facing 46. On end end of the shaft 43 there is keyed a grooved wheel 47.

On the shaft 12 of the crimping or scoring machine, in a line with the inking roller, 80 is a feed roll. This feed roll is constructed of metal and is of two parts, 48 and 49 respectively. The section 49 has openings 50 directed toward its end and reduced openings that register with the openings 50. 85 The section 48 has its ends provided with threaded orifices 51 that register with the last mentioned openings in the section 49. Arranged in the openings 50 are headed bolt members 52; the heads of the said bolts 90 are designed to be engaged by socket wrenches whereby the said bolts may be screwed in the threaded orifices 51, and also whereby the sections of the feed roll are connected and bound on the shaft 12.

On the shaft 11, directly opposite the feed roll is the printing or impression roll. This roll also comprises two sections 53 and 54, connected by bolts 55 in the same manner as are the sections of the feed roll. The sections 53 and 54 of the printing roll are, however, in the nature of shelves, which are, of course, semi-cylindrical in cross section so that the sections do not contact with the shaft 11. However, the printing or impression roll has secured therein, at or adjacent to its ends bearing rings 56. These rings are preferably constructed of bars and contact lightly with the shaft 11. On the outer periphery of the printing roll, and adjacent to the ends thereof, there is secured a pair of split bands 57 respectively. These bands are connected to the printing roll by screws 58, and to the opposite sides of the respective screws 58 are adjusting screws 49. The heads of the screws 58 and 59 are wholly received in the split bands 57. When the split bands 57 are to be held tight on the printing roll the screws 58 are screwed entirely home, and the screws 59, being of a length equaling the thickness of the bands are also screwed home. When the bands are to be adjusted away from the printing roll, the screws 58 are partly unscrewed, and the screws 59 are screwed homewardly into contacting engagement with the printing roll and inward of the periphery of the bands. Thus the bands may be arranged tightly against the printing roll and to a limited extent be positioned away from the same, and 130

through the medium of the screws, the said bands are effectively sustained in either of such positions. Thus the bands may be adjusted to engage with different thicknesses 5 of paper to facilitate the feeding operation thereof. It is to be noted that the combined length of the bands 57 are considerably less than a whole circle so that the confronting ends thereof are spaced a distance away 10 from each other and the ends of the oppositely disposed bearings of the bands are sustained in alinement with each other.

The printing or impression roll has, adjacent to its ends peripheral grooves. These 15 grooves each include an inner widened passage 60 and an outer reduced passage 61 that centrally communicates with the widened passage. Thus the grooves are T-shaped. The printing or impression roll has, at de- 20 sired points openings 62 that are of a size corresponding to the width of the widened passage 60 of the T-shaped slots. Through these openings heads of bolts 63 may be passed, and the said bolts move into the 25 T-shaped grooves. The bolts pass through suitable openings in a chase or other device 64 that carries the type 65. The bolts 63 are engaged by small nuts 66.

The type carrying or printing roller is 30 preferably integrally provided at its ends with grooves 67 and 68 respectively. These grooves are continuous and each of the same has secured therein a flexible element or cable 69, and each of these cables is trained 35 around one of the sheave wheels 32 and secured to the said sheave wheel. The printing or impression roller has at one of its ends a grooved wheel, and this grooved wheel receives therein a twisted belt 71, the 40 said belt being also trained around the grooved wheel 47 of the shaft of the inking roller.

Referring now particularly to Fig. 2 the 45 numeral 72 designates a paper board which may be crimped by the score rollers 13 and 14 and which is designed to have impressed thereon the printing matter carried by the printing or impression roller. Before proceeding further it should be fully understood 50 that the feed roller does not contact with the printing roller, and also that the spring 30 through the medium of the flexible elements or cables 69 that connect the same to the ends of the printing or impression roller, holds 55 the said roller against turning even when the shaft 11 is turned. It should also be understood that the type is arranged on the printing or impression roller a distance away from the confronting ends of the split 60 bands 57. When the paper 72 is fed between the feed and impression rollers, the same will be engaged by the split bands so that the paper board 72 will be positively fed between the rollers. The impression 65 roller will revolve in the direction of the

arrow in the said Fig. 2. The turning of the printing roller will also turn the ink roller so that the type on the impression roller will be properly inked. After the type is brought to engage with the paper board 72 70 the printing roller will have turned so that the ends of the split bands thereon will be brought opposite the feed roller as clearly disclosed in Fig. 4 of the drawings. As no frictional engagement is exerted between the 75 paper and the impression roller, and also as the spring 30 exerts a tension to return the roller to its initial or normal position, the paper 72 must pass entirely from between the rollers without further influencing the 80 printing or impression roller. After the paper has thus passed the spring will immediately return the printing roll to its normal position.

Of course any number of paper boards or 85 sheets 72 may have printed or other matter impressed thereon, but only one of such im- 90 presses may be made on a sheet. This in itself is a distinctly novel feature of the in- 95 vention. The type or other matter may be readily secured to or removed from the im- 100 pression roller, so that various classes of such matter may be impressed on the differ- 105 ent boxes manufactured. All of the parts of the improvement are extremely simple 110 and are not liable to get out of order. The device may be readily attached to a crimping or other box making machine without inter- 115 ferring with the operation of the machine or the parts thereof, and it is believed that the 120 foregoing description, when taken in connec- 125 tion with the drawings will fully set forth the construction and advantages of the im- 130 provement. While I have described the roll on the shaft 12 as a feed roll the same is really in the nature of a platen as the im- pression on the sheet to be printed is made thereagainst.

Having thus described the invention, what I claim is:—

1. A revolving platen, a normally station- 115 ary printing roll therefor, means actuated by a sheet to be printed for bringing the print- 120 ing roll to impression position when the sheet is arranged between the roll and platen, means for holding the printing roll against the influence of the sheet after an impression has been made thereon and after the print- 125 ing surface of the roll has been brought away from the sheet, and means for return- 130 ing the printing roll to initial position after the printed sheet has been brought from between the roll and platen.

2. Two revolving shafts, a combined feed and platen roll on one of the shafts, a print- 125 ing roll on the second shaft, means retaining the printing roll from influence by its shaft, said rolls designed to have the sheet to be printed fed therebetween and to contact therewith to cause the turning of the print- 130

ing roll to bring the impression surface thereof against the sheet and to further turn said roll to bring the impression surface away from the sheet after an impression has 5 been made thereon, and to also permit of the sheet passing between the rolls without further influencing the printing roll, and means for returning the printing roll to initial position after the sheet has been brought 10 from between the rolls.

3. In a printing attachment for box making machine, revolving shafts, a printing roll loose on one of the shafts, spring means for retaining the printing roll against influence 15 by its shaft, a combined feed and platen roll fixed on the other shaft, and means on the printing roll for engaging a sheet to be printed to cause the turning of the printing roll to bring the impression surface thereof 20 against the sheet and to further turn the roll to bring said impression surface off of the sheet and to hold the printing roll against further movement until after the printed sheet has been brought from 25 between the rolls.

4. In a printing attachment for box making machines, the combination with revolving shafts, of a printing roll loose on one of the shafts, spring means for sustaining the 30 printing roll from influence by its shaft, an inking roll for the impression surface of the printing roll, means actuated by the printing roll for reviving the inking roll when the first mentioned roll is turned, a combined feed and platen roll on the second shaft, means on the printing roll for engaging a sheet to be printed when the same is passed between said roll and platen roll, for causing the turning of the printing 35 roll against the influence of its spring means to bring the impression surface thereof against the sheet and to further turn the roll to bring the impression surface away from the sheet after the latter has been 40 printed, and to hold said roll against further movement, until after the printed sheet has been brought from between the rolls, and thereafter to permit of the influence of the spring means for returning the printing roll 45 to initial position.

5. In a printing attachment for box making machines, including two revolving shafts, a bracket supported on the machine, an inking roll carried thereby, a printing 55 roll loose on one of the shafts, a combined feed and platen roll fixed on the other shaft, spring means carried by the bracket, elements associated therewith and connected with the printing roll for influencing the latter to normally hold the same stationary, means carried by the printing roll and designed to be actuated by a sheet to be printed, when the latter is fed between the printing roll and the platen, for bringing the 60

impression surface of the printing roll 65 against the sheet to print the latter, and further move the printing roll to bring the impression surface away from the sheet and to hold the roll in such position until after the sheet has been brought from between the rolls, and thereafter to permit of the influence of spring means for returning the printing roll to initial position, and means actuated by the printing roll for turning the inking roll to bring the latter against 75 the impression surface of the printing roll.

6. In a printing attachment for paper box making machines including two revolving shafts for such machine; of adjustable supports on the frame of the machine, a shaft 80 secured thereto, a bracket on the shaft, means for sustaining said bracket angularly with respect to the shaft, said bracket including two longitudinally adjustable members, a spring having coiled ends on one of the bracket members; shafts connected to said ends, an inking roll journaled in bearings on the other bracket section, a printing roll loose on one of the shafts, means between said roll and the shafts of the spring 85 for normally sustaining the roller stationary, means between the printing roll and inking roll for revolving the latter when the former is turned, a combined feed and platen roll on the second shaft of the machine, 90 means carried by the printing roll and designed to be actuated by a sheet to be printed, when the latter is passed between the printing roll and platen roll, and for turning the printing roll to cause the impression 95 surface thereof to engage with the sheet, to further move said printing roll to bring the impression surface away from the sheet, and to hold said roll until after the sheet has been brought from between the rolls, and thereafter to permit of the spring means 100 influencing the roll to return the same to initial position.

7. In a printing attachment for box making machines, including two revolving 110 shafts; of a printing roll on one of the shafts, said roll comprising two sections, connecting means therefor, bearing means between the roll and the shaft, segmental bands on the outer periphery of the roll, 115 said roll having T-shaped slots, headed elements received therein, a type-containing case connected by said elements to the roll, a combined feed roll and platen on the second shaft, said last mentioned roll comprising two connected sections which are fixed to the shaft, spring means for holding the printing roll against the influence of its shaft, and an inking roll for the type 120 of the printing roll, as and for the purpose 125 set forth.

In testimony whereof I affix my signature.
ERNEST H. DUVAL.
